RUNNING BOARD AND THE LIKE

Thomas W. Delanty, Evanston, Ill., assignor to
 Apex Railway Products Co., Chicago, Ill., a
 corporation of Delaware

Application July 15, 1939, Serial No. 284,593

4 Claims. (Cl. 105—457)

This invention relates to improvements in running boards and the like, of the open grating type, and it consists of the matters hereinafter described and more particularly pointed out in the 5 appended claims.

The invention is more especially concerned with the means for attaching the running board to a support such as may be employed in connection with the roof of a railway car.

10 Heretofore it has been the practice to attach such boards to the support by means of U shaped bolts with the bend of the bolts engaged with a part of an associated bar and drawn down against the support by associated nuts. While this arrangement represented an advance in the art, it had certain disadvantages which the present invention seeks to overcome.

15 In drawing such U shaped bolts down tightly, the pull of both legs of the bolt is not always even and uniform and in a plane at a right angle to the support. This uneven pull of the U shaped bolt, has the tendency to twist the engaged bar with respect to others. Therefore, all of the bars of the board do not have that good firm engagement on the support, necessary to reduce the 20 tendency of the board to loosen from its support to the detriment of the safety factor of the board. Again, such U bolts require the use of two nuts each and this increases both the material cost and 25 the labor cost of application.

30 It has also been the practice to use hook bolts but these are likewise objectionable because the pull is exerted on one side so that the tendency is to twist the bars of the running board.

35 One of the objects of the present invention is to provide a simple though improved means for attaching a running board to the associated supports upon which it is engaged and which means is easier to apply and when applied provides a 40 uniform downward pull of the bars so that they do not become twisted or loosened so readily as with the means heretofore used.

Again, it is an object of the invention to provide a spanner element for cooperation with a 45 fastening bolt, which spanner element is so disposed as to be spaced upwardly from the bottom edges of the running board bars so that the bars alone engage the support.

Another object of the invention is to provide 50 an improved fastening means of this kind which does not project above the tread surface of the bars and which functions upon two adjacent bars simultaneously in a manner that does not tend to twist either bar but on the contrary acts to 55 hold said bars in a straight edgewise condition

for a better bottom edge engagement upon the associated support.

A further object of the invention is to provide attaching means of this kind which when the board is in place, is under tension and therefore resists the tendency of said means to loosen.

The above mentioned objects of the invention, as well as others, together with the advantages thereof will more fully appear as the specification 10 proceeds.

In the drawing:

Fig. 1 is a top plan view of the abutting ends of adjacent sections of a running board and associated parts of the roof of a railway car upon which the board is mounted.

Fig. 2 is a longitudinal vertical sectional view, on an enlarged scale, through parts appearing in Fig. 1 as taken on the line 2—2 of said Fig. 1.

Fig. 3 is a transverse vertical detail sectional view, on a further enlarged scale, through a part of the improved attaching means as taken on the line 3—3 of Fig. 2.

Fig. 4 is a longitudinal detail vertical sectional view of certain parts appearing in and on the scale of Fig. 3 as taken on the line 4—4 thereof.

Fig. 5 is a view similar to Fig. 3 showing a modified form of securing a certain plate member of the attaching means to two adjacent bars of the running board.

Fig. 6 is a plan view of the parts of the running board only appearing in Fig. 3 showing the use of a round shank bolt hole and bolt in the plate member of the attaching means.

Fig. 7 is a view similar to Fig. 6 and shows the use of a bolt having a rectangular shank portion for engagement in a correspondingly shaped hole in the plate member of the attaching means.

Referring now in detail to that embodiment of the invention illustrated in the accompanying drawing, 10—10 indicate the ends of a pair of abutting sections of the running board, said board being made in sections instead of one long length for economy in manufacture, installation and replacement due to collision or other damage.

Each section comprises a set of transversely spaced longitudinally extending, edgewise disposed metal bars 11—11 and a set of longitudinally spaced transversely extending bars 12—12. If desired, the running board sections may be made with one of the latter bars at each end 45 of each section. The bars of said sets may be secured together in operative relation in any suitable manner but as the same forms no part of the present invention, it need not be shown or described in detail. The top edges of the bars in 50 55 60 65 70 75 80 85 90 95

both sets are disposed in the same horizontal plane. While the bottom edges of the longitudinal bars are disposed in a horizontal plane, and the bottom edges of the transverse bars are disposed in a horizontal plane, said horizontal planes are disposed in different elevations. In this instance, the plane of the bottom edges of said longitudinal bars is the lower in elevation.

With the bars of both sets of bars arranged as described, it is apparent that said bars provide a grating, with the elongated openings 13 defined by said bars, extending longitudinally of the board.

In each of certain of the openings 13, I provide a plate member 14 which is fixed to the opposed bars forming the two sides of the opening. In this instance, in certain of the end and intermediate openings 13 of each running board section 10, I provide a plate member 14 of a width equal to the distance between the opposed faces of two longitudinal bars 11 and less than the distance between the opposed faces of two transverse bars 12—12. Preferably said plate members are made square so that a space is present between the ends of said plate member and the adjacent transverse bars.

Each plate member is arranged below the longitudinal median line of the associated bars 11 with its bottom face spaced above the plane of the bottom edges of said bars as appears in Fig. 3. The plate members 14 may be secured to the bars 11—11 in several different ways but welding is the preferred form. In said Fig. 3 the welding, which is indicated at 15, is made from the top side of the running board and in Fig. 5 the welding, which is indicated at 15a, is made from the underside of the running board. This last mentioned form is preferred because when said plate member is under tension, as will later appear, said welding provides a direct support for the plate member and the welding is placed under compression and not under tension as in Fig. 3.

The board sections 10—10 before described may be mounted on the roof of a railway car in the following manner: Assume that said roof includes metallic sheets 16 running transversely of the associated car body. Under such conditions, the abutting ends of the roof sheets are flanged upwardly as at 17 and an expansion strip 18 is disposed between said flanges. A cap strip 19 of inverted U shaped section is employed to cover said flanges with flange parts 19a of the cap strip overlying marginal parts of the sheets 16. In connection with the roof seam structure described, an angle bar 20 is located on each side of the cap strip with the horizontal flanges 21 facing outwardly from the cap strip and arranged in a plane spaced below the top edge of the cap strip at a distance corresponding to the height of the bars 11 of the running board. The vertical flanges 22 of said angle bars engage with the side faces of the cap strip and are riveted or bolted thereto as appears at 23 in Fig. 2. A sealing strip 24 is applied to the top margin of the cap strip 19 above the angle bar flanges 21 and said strip is formed with lateral flanges 25 that overlap upon the top surface of said horizontal flanges 21 of the angle bars. The sealing strip prevents the entrance of water between the sides of the cap strip and the vertical flanges 22 of the angle bars.

The horizontal flanges of the angle bars constitute supports upon which the bottom edges of the longitudinal bars 11—11 of each board section engage, with the plate member 14 arranged

above a portion of each horizontal flange. Of course, holes are formed in the flanges 21 of the angle bars and flanges 25 of the sealing strip to register with holes 26 in the plate members 14 of the running board sections 10—10.

When the ends of abutting running board sections are disposed upon said flanges 21, bolts 27 are inserted through the registering holes mentioned, with the head end of said bolts engaged on said plate members, after which nuts 28 are applied to the bottom ends of said bolts, and which bottom ends project below the bottom surface of said flanges. When bolts, having full length circular shanks are employed, then said plate members each have a round hole 14a therein, as shown in Fig. 6. When the plate members 14 are of the kind having the square hole 14b, as appears in Fig. 7, then the bolts employed are of the carriage bolt type and have squared portions on the shank that engage in said holes. This prevents the bolts from turning in the plate member and makes it easier to apply the nuts 28 thereto.

When the nuts 28 are drawn up tight on the bolts, the latter are placed under tension and in turn place the plate members under tension. This materially assists in preventing loosening of the nuts on the bolts. Also, when said nuts are drawn up tight, the ends of all of the bars 11 are drawn into a rigid seating engagement upon the flanges 21 of the angle bars 20.

As the plate members 14 are disposed below the longitudinal center of the bars 11—11, the downward pull of the bolts 27 does not tend to spread the bottom edges of the bars apart to twist them. Therefore, the pull of the bolts is a straight downward pull that insures a firm seating engagement of the bottom edges of the bars upon the supports provided by the flanges 21 of the angle bars 20—20. As the bottom surfaces of the plate-like members 14 are disposed slightly above the bottom edges of the bars, the pull on said plate members by the bolts is not affected, as would be the case were the plate members directly to engage said supporting flanges.

It is apparent that the pull of each bolt is transmitted directly to two adjacent longitudinal bars of each board section and this pull is exerted in a straight downward direction. Therefore, there is no tendency to twist either of the adjacent bars to warp them out of engagement with said flanges 21.

The improved fastening means is not only simple in construction, but it is indeed efficient in operation in holding the ends of the longitudinal bars of the running board sections evenly and rigidly upon the flanges of the supporting angle bars.

While in describing my invention, I have referred in detail to the form, arrangement and construction of the parts involved, the same is to be considered only in the illustrative sense so that I do not wish to be limited thereto except as may be specifically set forth in the appended claims.

I claim as my invention:

1. In combination with a part of a running board of the open grating type and including a set of vertically edgewise disposed bars extending generally in the same direction and having their bottom edges disposed in the same plane, a support below and upon which the bottom edges of said bars engage, an apertured plate-like element disposed entirely between and having two

opposite edges welded to the opposed faces of two adjacent bars with its upper surface arranged below the vertical mid points of said opposed faces and with its bottom surface arranged 5 slightly above the bottom edges of said two bars, and a bolt extending through the apertured plate-like element and having an associated nut securing said plate-like element to said support and functioning through said plate-like element 10 to draw the bottom edges of said two adjacent bars into a tight engagement with said support, said plate-like element holding the bottom marginal portion of said two adjacent bars against lateral outward spreading in the tightening of the bolt through its associated nut.

15 2. In combination with a part of a running board of the open grating type and including a set of vertically edgewise disposed bars extending generally in the same direction and having 20 their bottom edges disposed in the same plane, a support below and upon which the bottom edges of said bars engage, an apertured plate-like element disposed entirely between and having two opposite edges welded to the opposed faces of 25 two adjacent bars with its upper surface arranged below the vertical mid points of said opposed faces and with its bottom surface arranged slightly above the bottom edges of said two adjacent bars, and a bolt extending through the apertured plate-like element and having an associated nut securing 30 said plate-like element to said support and functioning through said plate-like element to draw the bottom edges of said two adjacent bars into a tight engagement with said support, said plate-like element having a thickness greater than that 35

of said bars and holding the bottom marginal portion of said two adjacent bars against lateral outward spreading in the tightening of the bolt through its associated nut.

3. As an article of manufacture, a running board section of the grating type comprising two sets of spaced apart bars, the bars forming one set being disposed at an angle to those in the other set, but being operatively secured thereto and at least one set being vertically edgewise, an 10 apertured plate-like element having opposed edges engaged with and welded to opposed faces of two adjacent bars in at least one set of vertically edgewise bars, with its upper surface arranged below the vertical mid points of said opposed 15 faces and with its bottom surface arranged slightly above the bottom edges of said two adjacent bars.

4. As an article of manufacture, a running board section of the grating type comprising 20 two sets of spaced apart bars, the bars forming one set being disposed at an angle to those in the other set, but being operatively secured thereto and at least one set being vertically edgewise, an apertured plate-like element of a thick- 25 ness greater than that of said vertically edgewise bars, having opposed edges engaged with and welded to the opposed faces of two adjacent bars in at least one set of vertically edgewise bars, with its upper surface arranged below the 30 vertical mid point of said opposed faces and with its bottom surface arranged slightly above the bottom edges of said two adjacent bars.

THOMAS W. DELANTY. 35
